PHASE MODULATION SYSTEM

Edouard Labin, Buenos Aires, Argentina, assignor to Hartford National Bank and Trust Company, Hartford, Conn., as trustee

Application March 20, 1944, Serial No. 527,286

10 Claims. (Cl. 179—171.5)

1

This invention relates to wave length modulation systems and more particularly to a system wherein the phase angle of a high-frequency oscillation is proportional to the amplitude of a modulating potential over a wide range of phase angle deviations.

In one type of prior phase modulation systems, the phase modulated oscillation is generated by vectorially combining the constant amplitude carrier wave with the side-bands whose amplitudes are linearly modulated in phase opposition. The main drawback of these systems is that a linear relation between the amplitude of the modulating intelligence and the resultant phase of the modulated oscillation can solely be maintained for phase angle deviations which do not exceed $\pm 30^\circ$. Furthermore, the modulation procedure also introduces a certain amount of amplitude modulation, so that amplitude limiter stages have to be used to obtain a pure phase modulated carrier oscillation.

In another type of known phase modulation systems wherein the resultant phase modulated oscillation is obtained by vectorially adding two linearly push-pull amplitude modulated oscillations having a phase difference smaller than π , the resultant phase angle is proportional to the modulating potential for small deviation angles only, so that a wide band phase modulation is still accompanied by relatively large variations in the amplitude of the modulated oscillation.

Leon Rubin has shown in the phase modulation system disclosed in U. S. patent application Serial No. 515,446 that by vectorially combining two non-linearly amplitude modulated oscillations of equal frequency having some optimum phase difference smaller than π , the phase angle of the resultant oscillation will be substantially proportional to the amplitude of the modulating potential for phase angle variations not higher than 60° and that within this range the amplitude of the phase modulated oscillation will remain practically constant.

I have now found that if the phase difference between two component oscillations of equal frequency and, simultaneously, the amplitude of one of these component oscillations are each varied as a convenient trigonometric function of the modulating potential, the vector sum of these component oscillations will constitute an oscillation of constant amplitude but having a phase angle varying between 0 and 180° degrees in accordance with the amplitude of the modulating potential.

In particular, I utilize antiphase or cophase fractions of a main oscillation as the constant amplitude component oscillation while the component oscillation of varying amplitude and phase is directly derived from the main oscillation by means of a network comprising a sus-

2

ceptance and conductance connected either in parallel or in series to a thermionic tube inserted between the main oscillation source and the output circuit of the phase modulation system and operating as an intermediate supply of constant current or constant voltage characteristics, respectively. I have found that by controlling the conductance in this network by means of the modulating potential so that the ratio between conductance and susceptance during a complete cycle of modulation will reproduce substantially the trigonometric tangent function of $\pi/2$ times the relationship between the instantaneous value of said modulating potential and its maximum value, the phase angle of the derived component oscillation will vary linearly with the amplitude of the modulating potential, whereas its amplitude will vary as the sine or cosine of said phase angle. Hence, the phase angle of the resultant vector sum oscillation will vary between 0 and 180° degrees proportionally to the amplitude of the modulation, but its amplitude will remain constant throughout the complete cycle of modulation. In a more concise form it can be stated that according to the invention the variable conductance is varied proportionally to the trigonometric tangent function of an angle proportional to the modulating potential.

It is therefore one of the main objects of the present invention to provide a phase modulation system wherein a linear relation between modulating potential and phase deviation of the modulated oscillation will be maintained over a range of 180° .

A further object of the present invention is to provide a phase modulation system in which a phase variation of 180° is obtained in an effective way by means of a circuit of simple layout.

The above and further features which I believe to be characteristic of my invention are set forth in the appended claims; the invention itself, however, as to both its organization and method of operation will be best understood by reference to the following description taken in connection with the drawings in which I have indicated several circuit layouts whereby my invention may be carried into effect.

In the drawings:

50 Fig. 1 is a wiring diagram of a phase modulation circuit according to the present invention.

Fig. 1a illustrates a modification of the circuit of Fig. 1.

Fig. 2 is a vector diagram given in order to explain the operation of the phase modulation circuit shown in Fig. 1.

Fig. 3 is another diagram relating to the operation of the phase modulation circuit shown in Fig. 1.

Fig. 4 illustrates a modification of the phase

60

modulation circuit according to principles of the invention.

Fig. 5 shows another modification.

Fig. 6 is a vector diagram explanatory of the operation of the phase modulation circuit shown in Fig. 5, and finally

Fig. 7 is a block diagram of a frequency modulation transmitter including a phase modulator according to the present invention.

Similar or like elements or parts are designated by the same reference characters and numerals throughout the drawings.

Referring now to Fig. 1 illustrating one embodiment of the phase modulation system according to the present invention, it can be seen that an oscillator 10 generating main oscillation

$$e = E_0 \sin \omega t$$

has its output terminals 11 and 12 coupled to cathode 13 and control grid 14, respectively, of a thermionic pentode tube V₁ the anode 15 of which is connected through a reactive circuit consisting of a slightly detuned resonant circuit A formed of an inductance 16 and capacitance 17, to the positive pole 18 of a direct current supply 19. Screen grid 20 of pentode V₁ is connected to a tap on direct current supply 19 the negative pole 21 of which is connected to ground potential together with cathode 13 of tube V₁ and terminal 11 of main oscillator 10.

Anode 15 of tube V₁ and the corresponding end of resonant circuit A are coupled to anode 22 of a triode tube V having its cathode 23 connected to ground potential, while its control circuit comprising control grid 24 is coupled to output terminals 25 and 26 of a modulator 27 generating a modulating potential S conveniently derived from the intelligence in accordance with the exact nature of the wave to be radiated, i. e. modulating potential S being proportional to the intelligence or to the time integral of the intelligence depending on whether a phase or a frequency modulated wave is to be transmitted. The intelligence is considered in this particular use to be a signal voltage the mathematical expression of which as a function of time is s(t) so that the time integral of the intelligence is represented by a quantity which is derived from the intelligence s(t) by an integrating device well known in the art the mathematical expression of which is K₁s(t) dt.

Considering resonant circuit A and triode V as susceptance B and conductance G, respectively, connected in parallel to a source of constant current represented by pentode V₁ i. e. that pentode V₁ has a sufficiently high internal resistance and is capable of maintaining the current supplied to network A independently of the load resistance presented by the latter, it will be understood that component oscillation W, developed between terminal 28 (coupled to anode 22 of triode V) and ground, can be expressed in terms of said susceptance B and conductance G as follows:

$$W = E \cos \varphi \cos (\omega t + \varphi)$$

where

$$\operatorname{tg} \varphi = \frac{G}{B}$$

Hence, component oscillation W may be represented by vector 29 having its phase shifted 90+ φ degrees with respect to the phase of vector 30 corresponding to main oscillation e, as can be observed in the vector diagram shown in Fig. 2. The relation between E and E₀ which depends on the net amplification of pentode V₁ has not

been precisely indicated since it is immaterial and does not alter the operation of the circuit.

Thus, by means of V₁ acting as a source of constant current coupled to a susceptance B and conductance G connected in parallel, main oscillation e is directly transformed into component oscillation W having a phase difference angle φ equal to the arctan of the ratio between conductance G of triode tube V and susceptance B of resonant circuit A, the amplitude of W being also a trigonometric function of said phase difference angle φ .

I have now found that by vectorially combining component oscillation W with another component oscillation e' = -0.5E cos ωt of constant amplitude and phase, an output oscillation

$$U = 0.5E \cos (\omega t + \psi)$$

of constant amplitude 0.5E but having a phase angle equal to two times phase difference angle φ will be obtained, so that a variation of phase difference angle φ of component oscillation W from zero to $\pm 45^\circ$ will cause phase angle of output oscillation U to vary from zero to $\pm 90^\circ$, as is evident from the aforementioned trigonometric formulae and as will be explained hereinafter with reference to the vector diagram and curves shown in Figs. 2 and 3 respectively.

As already explained hereinabove, the tangent of phase difference angle φ is equal by definition to the ratio of conductance G and susceptance B, so that by varying the conductance of triode tube V in accordance with the amplitude of modulating potential S, a variation of phase difference angle φ , and hence a corresponding variation of phase angle ψ of output oscillation U will be obtained. In the phase modulation system of Fig. 1 the operating conditions of triode V are so arranged that the relation of its internal conductance G with respect to control voltage e_g can be represented in Fig. 3 by curve 31, which, giving in fact the ratio of G to B, reproduces the tangent function between 0 and 90 degrees, control voltage e_g being proportional to the amplitude of modulating potential S visualized by curve 32 in the same figure.

In the absence of modulation, a potential S₀ equal to the voltage of the C-battery 33 (Fig. 1) is present at control grid 24 of triode V, the circuit parameters of the phase modulation circuit according to the present invention being adjusted so that in due absence of modulation, conductance G of triode V is equal to susceptance B of parallel resonant circuit A. The above operating condition is represented in the vector diagram of Fig. 2 by vector 34 which corresponds to output oscillation U in the absence of modulation and which represents the sum of vectors 35 and 36 representing component oscillations e' and W, respectively.

During a complete cycle of modulation, the amplitude of modulating potential S may vary about its mean value S₀ between the maximum negative and positive values S_{min} and S_{max}, respectively, so that in view of the tangent configuration of Fig. 3, the ratio between G and B will vary as illustrated by curve 31' shown in Fig. 3.

Hence, during a complete cycle of modulation, vector 36 centered on point 37 located at the end of vector 35, will oscillate about line 38 between a maximum negative angle φ' of -45° and a maximum positive angle φ' of $+45^\circ$, its amplitude simultaneously varying between zero and a value equal to the amplitude of vector 30.

The end of vector 36 will therefore describe a

semi-circle 39 during a complete cycle of modulation, and vector 34, representing phase modulated output oscillation U, will oscillate about line 40 corresponding to the output oscillation in absence of modulation as indicated by the arrow in the diagram of Fig. 2, its phase angle φ' varying between the extreme values of ± 90 degrees. Since vector 34 represents the radius of semi-circle 39, the amplitude of output oscillation U remains constant throughout the whole phase modulation range which covers a total of 180° and in which phase angle φ' is proportional to the amplitude of modulating potential S.

As can be seen in the circuit diagram shown in Fig. 1, the vectorial addition of component oscillation W and e' is carried out in a thermionic mixer tube V₂, the control grids 41 and 42 of which constitute the inputs for component oscillations W and e' , respectively. Control grid 41 is directly connected to terminal 28 of the parallel network, while control grid 42 is coupled to the secondary winding 43' of a transformer T, the primary winding 44 of which is coupled to output terminals 11 and 12 of main oscillator 10. Transformer T, is designed so that component oscillation e' applied to control grid 42 is of an amplitude equal to a convenient fraction of the amplitude of main oscillation e but has its phase rotated -90° with respect to the phase of main oscillation e. Said fraction is adjusted in accordance with the relation of the slopes of mixer tube V₂ with respect to control grids 41 and 42, so that the voltage fraction developed across load impedance Z of V₂ and corresponding to component oscillation e' will have half the amplitude of the voltage fraction corresponding to component oscillation W. Load impedance Z is formed of a resonant circuit tuned to the frequency of main oscillation e, so that the voltage between terminals 44 and 45 of said load impedance Z will represent the vector sum of component oscillation W and e' having a correct amplitude ratio as shown in the vector diagram of Fig. 2. The amplitude of output oscillation U will be constant while its phase angle will vary in accordance with the amplitude of modulating potential S, which in turn controls the variable conductance G connected in parallel with susceptance B and constituted by triode tube V.

As explained hereinbefore, in the phase modulation system according to the present invention, a phase variation of 180° degrees can be easily obtained by varying the phase of component oscillation W over a range of 90° only. Theoretically, such phase modulation requires a variation of conductance G between zero and infinity, but it will be understood that for all practical purposes it will be quite sufficient to vary conductance G between zero and a maximum value equal to at least ten times the value of susceptance B. The dotted portions 31'' of curve 31' shown in Fig. 3 have been drawn according to the above limitations which can be easily overcome by a judicious choice of a suitable valve type for triode V and by conveniently adjusting the operating conditions of the tube.

Although in the circuit diagram shown in Fig. 1 susceptance B is formed by parallel resonant circuit A, it should be noted that a capacitance alone can also be used for this purpose if the frequency of main oscillation e is below 1 mc./s., since for these relatively low frequencies the relation 1:10 between susceptance B and maximum value of available conductance G can be easily obtained. Only where the frequency of main oscillation e

is higher than 1 mc./s. the use of resonant circuit for susceptance B becomes necessary, since by tuning the resonant circuit to either side of resonance, the absolute magnitude of susceptance B can be easily adjusted to any desired value.

The above modification is illustrated in the circuit shown in Fig. 1a, where it is seen that the anodes of thermionic tubes V₁ and V are connected to the positive pole 18 of D. C. source 19 through a common choke coil 16', a capacitor 17' constituting the susceptance B being connected in parallel with variable conductance tube V. In other respects the phase modulator shown in Fig. 1a is exactly similar to that of Fig. 1.

Fig. 4 illustrates a circuit arrangement similar to that of Fig. 1, but differing therefrom in that variable conductance G is formed as the sum of the cathode conductance G_c and the plate-cathode transconductance G_m of a thermionic pentode tube V' connected as a cathode follower between parallel resonant circuit A and thermionic mixer tube V₂. Modulating potential S is applied to control grid 47 of pentode V', so that total conductance G connected in parallel across resonant circuit A, can be varied between a fixed minimum value determined by cathode resistance 46 and a maximum value depending upon the operating potentials of the tube electrodes.

The utilization for variable conductance G, of pentodes connected as cathode followers is particularly advantageous since the G_m-e_g characteristic of variable mu pentodes can be adjusted to perfectly reproduce the tangent function between zero and 90° degrees.

In the embodiment of the present invention shown in Figs. 1 and 4, phase modulated output oscillation U is obtained by vectorially combining component oscillation e' of constant amplitude and phase with component oscillation W of variable phase and amplitude derived from main oscillation e by means of a network comprising pentode tube V₁, susceptance B and conductance G connected in parallel. Fig. 5 illustrates a modification of the phase modulation system according to the present invention, differing from the circuits of Figs. 1 and 4 in that output oscillation U' is obtained by vectorially combining a component oscillation e'' of constant amplitude cophasally derived from main oscillation e with another component oscillation W' of varying phase and amplitude derived from main oscillation e by means of a network constituted of a triode tube V'₁ acting as a source of constant voltage and connected across a resonant circuit A' having a reactance L and connected in series with a triode tube V'' of an internal resistance R.

As can be seen in the circuit diagram shown in Fig. 5, output terminals 11' and 12' of output oscillator 10 generating main oscillation $e=E_0 \sin \omega t$ are connected to cathode 48 and control grid 49, respectively, of triode tube V'₁ the anode 50 of which is connected to one end of parallel resonant circuit A' constituted by an inductance 16' and capacitance 17'. The other end of resonant circuit A' is connected to anode 22' of triode tube V'', the junction point 51 between tube V'' and resonant circuit A' being connected to the positive pole 18' of a direct current supply 19' through choke coil 52. The negative pole 20' of direct current supply 19' is connected to ground together with terminal 11' of main oscillator 10' and cathodes 48 and 23' of triodes V'₁ and V'', respectively.

Modulating potential S' generated in modulator 27' is applied to control grid 24' of tube V'' to vary the internal resistance R of this tube in accordance with the amplitude variations of modulating potential S' as will be explained hereinafter, so that a component oscillation W' of varying phase and amplitude will be obtained between junction point 51 and ground.

In fact, considering triode tube V' as a source of constant voltage i. e. assuming that triode V' has a sufficiently low internal resistance and is capable of maintaining the voltage applied to network A' independently of the load represented by the latter, and assuming that resonant circuit A' is tuned so as to present a reactance L at the frequency of main oscillation e , it will be understood that component oscillation W' is substantially equal to $E \sin \varphi \cos(\omega t + \varphi)$, where

$$\operatorname{tg} \varphi = \frac{R}{L}$$

Hence, by vectorially combining component oscillation W' with component oscillation $e'' = 0.5 E \sin \omega t$, an output oscillation

$$U' = 0.5 E \sin(\omega t + \psi)$$

will be obtained where phase angle $\psi = 2\varphi$. Since

$$\operatorname{tg} \varphi = \frac{R}{L}$$

phase angle ψ of output oscillation U' can be modulated by varying internal resistance R of triode V'' in such a way that the ratio of resistance R to reactance L during a complete cycle of modulation reproduces a tangent function between zero and 90 degrees.

Actually, the operating conditions of triode tube V'' are similar to those of triode tube V in the circuit shown in Figs. 1 and 4. Consequently, in the vector diagram shown in Fig. 6, vector 53' representing output oscillation U' in the absence of modulation is equal to the sum of vectors 54 and 55' corresponding to component oscillations e'' and W' , respectively.

As can be seen in the diagram, vector 54 is in phase with vector 56 representing main oscillation $e = E_0 \sin \omega t$, the relation between the scalar values of vectors 54 and 56 corresponding to the amplitude relations of the respective oscillations. During a complete cycle of modulation, vector 55 corresponding to the instantaneous value of component oscillation W' will oscillate about line 57 while being centered on point 58 located at the end of vector 54. The maximum phase difference angle φ' between line 57 and vector 55 is equal to $\pm 45^\circ$, while the amplitude of vector 55 varies between a value equal to the amplitude of main oscillation e and zero.

Hence, during modulation vector 53 will oscillate $\pm 90^\circ$ about line 59 and describing with its end semi-circle 60, so that its amplitude and consequently the amplitude of output oscillation U' will remain constant over the entire range of variations of phase angle ψ .

Component oscillation W' is applied to control grid 41' of a thermionic mixer tube V'2, while component oscillation e'' is derived from main oscillation e by means of a potentiometer P connected to oscillator terminals 11' and 12', control grid 42' of thermionic mixer tube V'2 being connected to the junction point of resistances 61 and 62 constituting potentiometer P.

Resistances 61 and 62 are designed so that the voltage fraction corresponding to e'' and developed across load impedance Z' of mixer tube V'2 is equal to half the amplitude of the voltage

fraction corresponding to component oscillation W' , so that phase modulated oscillation U' appears as the vector sum of both component oscillations W' and e'' between output terminals 5 44' and 45' connected to said load impedance Z' which is constituted by a resonant circuit tuned to the frequency of main oscillation e .

It will be evident that in the phase modulation circuit shown in Fig. 5, triode tube V' acting 10 as a variable resistance R can be replaced by a pentode connected as cathode follower as shown in Fig. 4 without affecting the correct operation of the system. Similarly, the vectorial addition of component oscillations e' , W or e'' , W' may 15 also be carried out by applying both oscillations to a common control grid of a thermionic tube which would develop the phase modulated output oscillation in its plate circuit. It should be noted, however, that a suitable thermionic separating 20 stage should be inserted in the connection coupling main oscillator 10 to the control grid of the mixer tube in order to prevent the generation of parasitic oscillations in the circuit.

Fig. 7 illustrates the utilization of one of the 25 phase modulation circuits according to the present invention in a frequency modulation transmitter. As can be seen in the drawings, output terminals 44 and 45 of the phase modulator designated by the general reference numeral 63 are 30 coupled to a frequency multiplier stage 64 connected in turn to a power amplifier stage 65 provided with an antenna 66, so that the frequency of the radiated carrier wave will vary in accordance with modulating potential S generated 35 in modulator 27.

As stated above, it should be understood that the modulating potential S is proportional to the time integral of the intelligence to be transmitted, since it is desired to radiate a wave modulated in frequency and for this purpose a voltage 40 integrator 27' is interposed between the modulation source 27 and the tube V.

While I have shown only particular embodiments of my invention, it will of course, be understood that I do not wish to be limited thereto since many modifications may be made without departing from the spirit and scope of my invention as defined in the following claims.

I claim:

1. A system for modulating the phase of an 50 electrical oscillation in accordance with a modulating potential, which comprises a source of main oscillations coupled through a means of constant output current characteristics to a network constituted by a susceptance and a variable conductance connected in parallel, means to vary said conductance proportionally to the tangent of an angle proportional to the amplitude of said modulating potential to produce a first component oscillation having a phase angle varying as the ratio of said conductance to said susceptance and an amplitude varying proportionally to the cosine of the said phase angle, means to derive a second component oscillation of constant amplitude and in lagging phase quadrature with respect to said main oscillation, and means to vectorially combine said first and second component oscillations to produce a resultant oscillation of constant amplitude having a phase angle linearly proportional to the amplitude of said modulating potential.

2. In a system for modulating the phase angle 60 of an electrical oscillation, a thermionic pentode tube having a control electrode, a cathode and an anode, a source of main oscillations connected 65

between said cathode and said control electrode, a network comprising a susceptance circuit element and a variable conductance connected in parallel, said variable conductance being constituted by the anode-cathode conductance of a thermionic triode tube having a control electrode, a cathode and an anode, said triode tube having a response characteristic with respect to the control electrode voltage at which the ratio of the triode conductance to the said circuit susceptance is substantially proportional to the tangent function from zero to $\pi/2$, means to connect one end of said susceptance circuit and the anode of said triode tube to the anode of said pentode, means to connect a source of modulating potential to the control electrode of said triode tube to produce a first component oscillation having a phase angle varying in accordance with the ratio between said anode-cathode conductance and the susceptance of said susceptance circuit and an amplitude varying proportionally to the cosine of the said phase angle, means to derive a second component oscillation of constant amplitude and in lagging phase quadrature with respect to said main oscillations, and means to vectorially combine said first and second component oscillations to produce a resultant oscillation of constant amplitude having a phase angle linearly proportional to the amplitude of said modulating potential.

3. In a system for modulating the phase angle of an electrical oscillation, a thermionic pentode tube having a control electrode, a cathode and an anode, a source of a main oscillation connected between said cathode and said control electrode, a network comprising a susceptance circuit constituted by parallel resonant circuit elements and a variable conductance connected in parallel, said variable conductance being constituted by the anode-cathode conductance of a thermionic triode tube having a control electrode, a cathode and an anode and having a response characteristic with respect to the control electrode voltage at which the ratio of the triode conductance to the said circuit susceptance is substantially proportional to the tangent function from zero to $\pi/2$, means to connect one end of said parallel resonant susceptance circuit and the anode of said triode tube to the anode of said pentode, means to connect a source of modulating potential to the control electrode of said triode tube to produce a first component oscillation having a phase angle varying as the ratio between said anode-cathode conductance and the susceptance of said resonant circuit and an amplitude varying proportionally to the cosine of the said phase angle, a transformer having a primary and an unloaded secondary winding, means to connect said primary winding to said main oscillation source to produce across said secondary winding a second component oscillation of constant amplitude and in lagging phase quadrature with respect to said main oscillation, a thermionic mixer tube having two control electrodes and an anode loaded by a circuit tuned to the frequency of said main oscillation, and means to connect the control electrodes of said mixer tube to said network and to said unloaded secondary winding, respectively, to produce in said load circuit a resultant oscillation of constant amplitude equal to the vector sum of said first and second component oscillations and having a phase angle linearly proportional to the amplitude of said modulating potential.

4. A phase modulator system according to claim 3, wherein the maximum amplitude of said first component oscillation in said load circuit is equal to two times the amplitude of said second component oscillation in the same load circuit.
5. In a system for modulating the phase angle of an electrical oscillation, a thermionic pentode tube having a control electrode, a cathode and an anode, a source of a main oscillation connected between said cathode and said control electrode, a network comprising a susceptance circuit constituted by parallel resonant circuit elements and a variable conductance connected in parallel, said variable conductance being constituted by a thermionic pentode tube having a control electrode, a cathode and an anode and a resistance connected in series with said cathode and anode and connected in shunt with said susceptance circuit, said second pentode tube having a response characteristic with respect to the control electrode voltage at which the ratio of the said conductance to the said circuit susceptance is substantially proportional to the tangent function from zero to $\pi/2$, means to connect said susceptance circuit and said conductance to the anode of said first pentode tube, means to connect a source of modulating potential to the control electrode of said second pentode to produce a first component oscillation having a phase angle varying proportionally to the ratio between said conductance and the susceptance of said network and an amplitude varying proportionally to the cosine of the said phase angle, means to derive a second component oscillation of constant amplitude and in lagging phase quadrature with respect to said main oscillation, and means to vectorially combine said first and second component oscillations to produce a resultant oscillation of constant amplitude having a phase angle linearly proportional to the amplitude of said modulating potential.
6. A system for modulating the phase of an electrical oscillation in accordance with a modulating potential, which comprises a source of a main oscillation coupled through a means of constant output voltage characteristics to a network consisting of a reactance and a variable resistance connected in series, means to vary said resistance proportional to the tangent of an angle proportional to the amplitude of said modulating potential to produce a first component oscillation having a phase angle varying in accordance with the ratio between said resistance and said reactance and an amplitude varying proportionally to the sine of the said phase angle, means to cophasally derive a second component oscillation of constant amplitude from said main oscillation, and means to vectorially combine said first and second component oscillations to produce a resultant oscillation of constant amplitude having a phase angle linearly proportional to the amplitude of said modulating potential.
7. In a system for modulating the phase angle of an electrical oscillation, a thermionic triode tube having a control electrode, a cathode and an anode, a source of a main oscillation connected between said cathode and said control electrode, a network comprising a reactance circuit constituted by parallel resonant circuit elements and a variable resistance connected in series, said variable resistance being constituted by the internal resistance of a second thermionic triode tube having a control electrode, a cathode and an anode, said second triode tube having a response char-

acteristic with respect to the control electrode voltage at which the ratio of the triode internal resistance to said circuit reactance is substantially proportional to the tangent function from zero to $\pi/2$, means to connect the end of said resonant circuit remote from the anode of said second triode to the anode of the first triode tube, means to connect a source of modulating potential to the control electrode of said second triode tube to produce a first component oscillation having a phase angle varying proportional to the ratio between said internal resistance and the reactance of the parallel resonant circuit elements and an amplitude varying proportionally to the sine of the said phase angle, means to cophasally derive a second component oscillation of constant amplitude from said main oscillation and means to vectorially combine said first and second component oscillations to produce a resultant oscillation of constant amplitude having a phase angle linearly proportional to the amplitude of said modulating potential.

8. In a system for modulating the phase angle of an electrical oscillation, a thermionic triode tube having a control electrode, a cathode and an anode, a source of a main oscillation connected between said cathode and said control electrode, a network comprising a reactance circuit constituted by parallel resonant circuit elements and a variable resistance connected in series, said variable resistance being constituted by the internal resistance of a second thermionic triode tube having a control electrode, a cathode and an anode, said second triode having a response characteristic with respect to the control electrode voltage at which the ratio of the triode internal resistance to the said circuit reactance is substantially proportional to the tangent function from zero to $\pi/2$, means to connect the end of said resonant circuit remote from the anode of said second triode to the anode of the first triode tube, means to connect a source of modulating potential to the control electrode of said second triode tube to produce a first component oscillation having a phase angle varying proportional to the ratio between said internal resistance and the reactance of the parallel resonant circuit elements and an amplitude varying proportionally to the sine of the said phase angle, two resistances connected in series and coupled to said main oscillation source to produce across one of said resistances a second component oscillation of constant amplitude in-phase with said main oscillation, a thermionic mixer tube having two control electrodes and an anode loaded by a circuit tuned

to the frequency of the main oscillation, and means to connect the control electrodes of said mixer tube to the anode of said second triode tube and to the junction point between said resistances, respectively, to produce in said load circuit a resultant oscillation of constant amplitude equal to the vector sum of said first and second component oscillations and having a phase angle linearly proportional to the amplitude of said modulating potential.

9. A system for modulating the phase angle of an electrical oscillation in accordance with a modulating potential, which comprises a source of main oscillation, a network comprising a susceptance and a variable conductance coupled to said source, means energized by said modulating potential to vary said conductance proportional to the trigonometric tangent function from zero to $\pi/2$ of an angle proportional to the amplitude of said modulating potential to produce a first component oscillation having a phase angle varying as the ratio of said conductance to said susceptance and an amplitude varying as a trigonometric function of said phase angle, means to derive a second component oscillation of constant amplitude and phase with respect to said main oscillation, and means to vectorially combine said first and second component oscillations to produce a resultant oscillation of constant amplitude having a phase angle linearly proportional to the amplitude of said modulating potential.

10. A system for modulating the phase of an electrical oscillation in accordance with a modulating potential, which comprises a source of main oscillations coupled through a means of constant output current characteristics to a network constituted by a capacitance and a variable conductance element connected in parallel, means to vary said conductance proportionally to the trigonometric tangent function from 0 to $\pi/2$ of an angle proportional to said modulating potential to produce a first component oscillation having a phase angle varying as the ratio of the conductance of said element to the susceptance of said capacitance and an amplitude varying proportionally to the cosine of the said phase angle, means to derive a second component oscillation of constant amplitude and in lagging phase quadrature with respect to said main oscillation, and means to vectorially combine said first and second component oscillations to produce a resultant oscillation of constant amplitude having a phase angle linearly proportional to the amplitude of said modulating potential.

EDOUARD LABIN.
